Southgate & Southgate.

UNITED STATES PATENT OFFICE.

HENRY W. GOVIN, OF NORTHBORO, MASSACHUSETTS.

FEED-WEIGHT ADJUSTMENT.

Application filed February 14, 1922. Serial No. 536,544.

To all whom it may concern:

Be it known that I, HENRY W. GOVIN, a citizen of the United States, residing at Northboro, in the county of Worcester and 5 State of Massachusetts, have invented a new and useful Feed-Weight Adjustment, of which the following is a specification.

This invention relates to an adjusting device for the feed weight of a self feed for a 10 carding machine.

The principal object of the invention is to provide efficient means for adjusting the weight for controlling the operation of the feed in such a way as to secure a very fine 15 control and to permit of the automatic operation of the feed when the amount of material in it has reached a certain predetermined amount, capable of being set so that this amount can be predetermined down to 20 a very fine degree of adjustment; also to provide a device of this kind in which the adjustment can be set and locked and will not vary unless intentionally adjusted.

Reference is to be had to the accompanying 25 drawings, in which—

Figure 1 is a side view of the top portion of a Bramwell card with a preferred embodiment of this invention applied thereto;

Fig. 2 is an end view of the same;

Fig. 3 is an enlarged side view of the adjusting device, and

Fig. 4 is a sectional view on the line 4—4 of Fig. 3.

As is well understood in this kind of a 35 machine, the wool is put in a large box in the top of the card. This box has a grating for the exit of refuse and means for raising the material out of the case until it is near the top where it is brought under 40 the action of an oscillating comb having a slow but long sweep. The teeth of the comb carry off the surplus wool from the elevating device, dropping it back in the box. Thus, what is left is evenly distributed and 45 it is carried over the top of a roller where it is taken off by a carrier provided with flexible strips that sweep the wool off and convey it into the scale pan 11. This scale pan is formed of two covered wings suspended 50 by steel knife edges 12. These wings are connected to two levers 13 and 14 pivotally connected together and on the latter is an arm 15 provided with a slidably weight 55 16. When the scale has received the proper amount of material the weight of it, overcoming the resistance of the weight 16,

moves a small trigger which causes an automatic mechanism that is well known to disengage the driving belt of the elevating device, thus instantly stopping the further delivery to the scale pan which now remains at rest. When the proper time arrives, the wings are opened and the wool is deposited on a feed apron 19 below. The scale pan is now closed and returned for more wool and the elevator is set going at the same time and the delivery repeated.

The above mentioned parts are not shown in full because they constitute the elements of the well known Bramwell self feed. This 70 invention can be applied to that one or to the other ones of similar type equally well and it relates to the weight 16 above mentioned. This weight, as stated, is adjustable along the arm 15. It is provided as usual with a passage through it through which the arm passes. I have shown the weight as of square instead of the usual round construction and into the vertical side above or below the arm 15 is screwed a screw threaded 75 rod 21 parallel with the arm 15. This screw is arranged to pass into the screw threaded opening in the weight any desired distance for adjusting purposes. On the end of the screw it is provided with an adjusting toothed wheel 22 fixed to it at a distance 80 from the weight. Pivotaly mounted on the screw by arms 23 and straddling the wheel 22 is a plate 24. This plate has a passage for the arm 15 of the same shape as the arm 90 and the passage through the weight and is provided with a set screw 25 for fixing it to the arm 15 at any desired point thereon.

Also mounted on the screw is a nut 27 having a handle 28 adapted to move up against the forward side of the weight. This is for the purpose of locking the screw to the plate in any desired position but it is never intended to be moved except through a small arc as indicated in Figs. 1 and 2. On the 100 plate 24 is a spring pressed pawl 29 for engaging the toothed wheel.

It will be understood that the weight is not provided with the usual set screw for fixing it in adjusted positions to the arm 15 105 but this adjustment is secured entirely by the screw. The operation will be obvious. The plate 24 is fixed to the arm 15 in any desired position by means of its set screw and now the adjusting screw can be rotated 110 after loosening the nut 27 to draw the weight along the arm and leave it in any desired

position thereon. The rotation of the screw throughout an entire revolution will advance the weight the distance of the pitch of the screw thread. As there are several equally spaced teeth on the adjusting wheel 22 it is obvious that the operator can divide that distance into an equal number of divisions in a positive and simple manner by turning the wheel through the space of one tooth. In this way the weight can be adjusted and set a short enough distance so that the amount of wool or other fiber that is deposited on the apron of the card each time the self feed device works can be varied down to the finest limits. In this way the irregularities in the feed and the coarseness of the previous adjustments are entirely eliminated. The operator simply adjusts this until he gets the exact amount that is required and then the adjustment does not have to be varied as long as the machine is working on the same kind of stock.

Although I have illustrated and described only a single form of the invention and shown it as applied to a particular type of self feed, I am aware of the fact that modifications can be made in the construction of the device and that it can be applied to other self feeding systems without departing from the scope of the invention as expressed in the claims.

Therefore, I do not wish to be limited to all the details of construction or to the particular type of self feed herein shown and described but what I do claim is:—

1. In a self feed for carding machines, the combination with a scale pan and an arm movable therewith, of a weight carried directly by, and movable along, the arm, means adapted to be fixed to the arm below the

weight for holding the weight at any desired point therealong, a ratchet wheel connected with said means, and a ratchet pawl connected with the arm for holding the ratchet wheel and weight in adjusted positions.

2. In a self feeding device for carding machines, the combination with a scale pan for receiving the fibrous material, an arm connected with the scale pan for controlling its operation, a weight slidable along the arm for adjustably counterbalancing the scale pan, a rod connected with the weight by a screw threaded connection, a toothed wheel fixed on the rod, a plate movably mounted on the rod and having a passage through which said arm passes, means for securing the plate fixedly to the arm, and means for engaging the toothed wheel and holding it in its adjusted positions.

3. In a self feeding device for carding machines, the combination with a scale pan for receiving the fibrous material, an arm connected with the scale pan for controlling its operation, a weight slidable along the arm for adjustably counterbalancing the scale pan, a screw connected with the weight, a toothed wheel fixed on the screw, a plate pivotally mounted on the screw and having a passage through which said arm passes, means for securing the plate fixedly to the arm, a spring pressed pawl on the plate for engaging the toothed wheel and holding it in its adjusted positions, and a nut having a handle on the screw adapted to bear against the weight to lock the screw in its adjusted positions.

In testimony whereof I have hereunto affixed my signature.

HENRY W. GOVIN.
